UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

RAILWAY-CAR END WALL.

Application filed March 8, 1926. Serial No. 93,256.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

My invention relates to the construction of a railway car having an end wall made of one or more metallic plates or panels secured together and formed with integral reinforcing and stiffening means to resist the thrust of shifting loads. While efforts are made to block the lading in the car, the shocks caused by the heavy locomotives, the emergency air brake and the classification hump tear the lading away from its moorings and throw it against the end of the car. The invention is readily adaptable to box, gondola and other types of railway cars.

One of the objects of the invention is to provide a wall element which has great strength to resist the torsional and weaving stresses which exist in a railway car when moving in service. These stresses are caused by the inertia of the roof and superstructure when the train is suddenly stopped; rough or uneven track; the superelevation of the track on curves; the lateral inertia in rounding curves; eccentric thrust due to the lading being secured to one side of the car; the cars being "cornered"; the use of push pole pockets, etc. Such stresses rack and distort the superstructure which decreases the life of the car, and also causes the car to leak grain, sand, and other such material. Furthermore, such stresses cause leaky roofs and leaky and inoperative side and end doors.

An object of the invention is to form the meeting edges of the metallic plates of an end wall so as to provide an integral stiffener or beam.

Another object is to form a depressed panel in one of the metallic plates of an end wall which strengthens that plate and also provides a bearing surface for lining boards, which paneled plate is used in combination with a substantially flat plate to complete the end wall of the car.

In the drawings:

Fig. 1 shows an end elevation of a rail-

way car with my invention applied thereon.

Fig. 2 is a section on line 2—2 of Fig. 1.

Fig. 3 shows a modified form.

Fig. 4 is a section on line 4—4 of Fig. 1.

The end wall comprises at least two plates secured together to form a panel, which panel is secured to the adjacent frame members of the car, such as the end sill 1, end plate 2 and corner post 3.

One of the metallic plates (4) has its central portion offset to form a continuous web 5 with a marginal portion 6 surrounding the continuous web. The other plate 7 underlaps a part of the offset portion of the plate 4 and has the marginal part of the underlapping portion bent (8) and flanged (9) to conform to the depression in the plate 4. Means are provided, such as rivets 10 and 11 to secure the edges of each plate to the other plate.

In the construction shown in Figs. 1 and 2 the upper plate 4 is provided with an offset central portion and the lower plate 7 is flat (with the exception of its marginal edges) and an additional lining or railing strips 14 are provided between the thin lining 12 and the flat metallic plate 7 which strengthens the lower portion of the end wall. Experience shows that an end wall should be stronger adjacent the floor.

In the construction shown in Fig. 3 the lower plate 20 is provided with an offset panel and the upper plate 21 is made flat (with the exception of its marginal edge). In this construction the thin lining 12 bears directly against the offset portion in the plate 20 and railing strips 13 are provided which are secured to the upper flat plate 21.

I claim:

1. An end wall for a railway car comprising a lower metallic plate having an offset central portion forming a continuous web, an upper metallic plate overlapping a portion of said offset central portion, having its lower part bent and flanged to conform to the offset in the other plate, and means to secure the edge of each plate to the other plate.

2. An end wall for a railway car comprising a lower metallic plate having an offset central portion forming a continuous web, an upper metallic plate overlapping a portion of said offset central portion, having its lower part bent and flanged to conform to the off-

set in the upper plate, means to secure the edge of each plate to the other plate, and a wooden lining bearing against said offset portion.

- 5 3. An end wall for a railway car comprising a lower metallic plate having an offset central portion forming a continuous web, an upper metallic plate overlapping a portion of said offset central portion, having its 10 lower part bent and flanged to conform to the offset in the upper plate, means to secure the edge of each plate to the other plate, a wooden lining bearing against said offset portion, and nailing strips attached to

said upper plate to which said lining is secured. 15

4. An end wall for a railway car comprising an upper and a lower metallic plate, one of said plates having an offset central portion forming a continuous web, and the 20 other of said plates overlapping a portion of said central portion with its overlapping portion bent and flanged to conform to the offset of the other plate, and means to secure the adjacent edge of each plate to the 25 other plate.

GARTH G. GILPIN.
